UNITED STATES PATENT OFFICE.

EDWIN D. TILLSON, OF CHICAGO, ILLINOIS, ASSIGNOR TO ASSOCIATED ENGINEERS COMPANY, OF CHICAGO, ILLINOIS.

LAMP-GUARD.

1,349,392.

Specification of Letters Patent. Patented Aug. 10, 1920.

Application filed February 18, 1918. Serial No. 217,872.

To all whom it may concern:

Be it known that I, EDWIN D. TILLSON, a citizen of the United States, residing at Chicago, in the county of Cook and State of Illinois, have invented a certain new and useful Improvement in Lamp-Guards, of which the following is a full, clear, concise and exact description, reference being had to the accompanying drawings, forming a part of this specification.

My invention relates to lamp guards and has for its object the provision of an improved guard so constructed that it prevents the failure of lamps carried therein. The quite universal use of lamps having filaments of the more breakable types, such as the tungsten type or types in which jars may cause contact between filament convolutions, thereby causing them to adhere together permanently, makes it necessary to provide means for holding these lamps within guards for those places where the lamps are used, for instance, at the extremities of extension cords or under similar conditions where the lamps are subject to violent jars.

In order to provide a suitable guard I have made many experiments including the use of guards in which springs are used as the sole means of absorbing the shock. I find that in order to prevent breakage of the lamp filament, or short circuiting of said filament, by springs alone, that the guard may be of such dimensions that it renders it practically undesirable, or at the very least, renders it subject to many grave objections.

I find, however, that if in addition to spring shock absorbing means I also arrange the lamp mounting within the guard in a manner to oppose frictional resistance to the movement of the lamp from one position to another that I am enabled to reduce the guard to a size within reasonable limits and still prevent failure of the lamp. I find, of course, that either the frictional resistance alone or the universal spring mounting alone might answer to prevent failure of the lamp, provided in the case of the frictional mounting, some suitable means are provided to return the lamp to its normal central position. In addition, I find it desirable frequently to construct the guard framework itself in a manner to provide resilience.

However, my experiments lead me to believe that the combination of the frictional mounting and the spring absorbing means is the most effective, although as before stated, it is possible to carry out my invention by the use of one or the other alone. Now, it will be readily understood that the initial movement of the lamp is retarded by the friction due to the frictional mounting between the relatively movable parts and that the retardation, if plotted, in the form of a curve would be practically a straight line. The retardation offered by the spring would of course be gradually increased from zero at the initial movement of the lamp to the maximum when the lamp has reached its final position of displacement. Springs cannot be used which are too strong and if the right kind of a spring is used, too much throw may be permitted the lamp to bring the guard within commercial requirements as to size.

With the combination of frictional retarding means and spring retardation, I am enabled to obtain almost a straight line curve, which will bring the lamp to a stop within a guard of reasonable size.

I will explain one form of carrying out my invention more in detail by referring to the accompanying drawings, in which—

Figure 1 is a side view of a guard constructed in accordance with my invention; Fig. 2 is a top view thereof; Fig. 3 is an enlarged fragmentary view similar to that of Fig. 1, certain parts being shown in section more clearly to reveal features of construction;

Fig. 4 is a side view partly in section similar to the view of Fig. 3 but showing a modified form of the invention in which my improved guard is applied to a socket already in use;

Fig. 5 is a fragmentary sectional view on line 5—5 of Fig. 4.

Referring more particularly to Figs 1, 2 and 3, my improved device includes an electric lamp socket 10, the shell of which has an outwardly flaring upwardly projecting spherical extension 11. The spherical extension 11 co-operates with a fragmentary spherical element 12 frictionally held by the cap 13. The cord 14 is shown projecting through the hollow elements 11, 12 and 13

directly into the socket 10. The cap 13, through the agency of the nut 15 is frictionally secured to the pan shaped plate 16. This plate 16 has a plurality of guard arms 17 fastened thereto and extending downwardly therefrom so as to encircle the lamp 18 carried by the socket 10. The arms 17 preferably have their extremities united by a ring 19. If desirable, a further ring 20 may be 10 added to give stability to the structure. I find it preferable, however, to omit such intermediate rings, thus improving the resilience of the guard framework. The socket 10 also carries a split ring 21 fastened there- 15 to, which ring has downwardly extending fingers 22. The fingers 22 and ring 21 being rigid and both being frictionally secured to the socket 10. The fingers 22 are at their extremities united by means of springs 23 with certain of the arms 17, the illustration 20 herein contemplating four springs 23 but eight arms 17. There is preferably no connection between the elements 11 and 12 other than frictional and these parts are held in 25 their frictional engagement due to the tension of the springs 23, these springs pulling these parts 11 and 12 together and exerting a pressure so that there is a certain amount of friction between the elements 11 and 12, which friction tends to retard relative movement between these elements 11 and 12.

The mode of operation of the device will thus be apparent. If the guard together with 35 the lamp is dropped or given any jar, then the lamp 18 will of course move away from its central position and immediately occupy the position as shown by dotted lines in Fig. 1. This movement of the lamp from 40 the central position is retarded by the friction between the elements 11 and 12, this friction being proportional to the strength of the springs 23. At the first initial movement of the lamp the springs 23 do not exert 45 a very great retarding influence. The frictional retarding influence however is quite constant. As the lamp moves farther away from its central position the retarding influence of the springs becomes stronger until 50 finally the lamp is brought to rest without any serious jar. Ears 30 are provided to prevent more than a predetermined amount of rotation of the lamp socket when inserting or withdrawing a lamp. The construction 55 of the guard is such that its upper restricted portion serves as a handle, and that its lower wide-open mouth permits it to stand on the floor or table as may be desired.

In Figs. 4 and 5, I have shown a modified 60 form in which the element 11^a is the cover plate of the element 11 in Fig. 3 with the exception that it has a downwardly extending hood 24 which is split and which may be frictionally mounted upon a socket 25 of the 65 standard type and held in place by means

of the locking screw 26. The arms 22^a may then preferably project downwardly directly from the element 11^a.

From what has been thus described the nature of my invention will be readily clear 70 to those skilled in the art as will also its application to other conditions.

I claim as my invention:

1. A lamp guard having a movably mounted lamp support therein, frictional retarding means tending to oppose the movement of said support, and resilient means connecting the guard to the support and controlling the friction of said retarding 80 means.

2. A lamp guard having a movably mounted lamp support therein, frictional retarding means tending to oppose the movement of said support, and springs connecting the guard to the support to maintain 85 said support in a central position and control the friction of said retarding means.

3. A lamp guard having a movably mounted lamp support therein, frictional retarding means tending to oppose the movement of said support, resilient means connecting the guard and support for controlling said friction means, and means to prevent rotation of said support.

4. A lamp guard having a movably mounted lamp support therein, frictional retarding means tending to oppose the movement of said support, and fingers forming part of said support and adapted to surround said lamp.

5. A lamp guard having mounted therein frictionally controlled means for yieldingly holding a lamp, fingers forming part of said frictionally controlled means and surrounding said lamp, and resilient means 105 connecting said frictionally controlled means to said guard for controlling the movements of said frictionally controlled means.

6. A lamp guard having a movably mounted lamp support therein, frictional retarding means tending to oppose the movement of said support, resilient means for controlling said frictional means, and fingers on said guard and adapted to surround 115 said lamp, said resilient means connecting the guard to the fingers.

7. A device of the character described comprising a plate member, a cap secured thereto, a spherical element contacting said cap, a socket, an extension on said socket for engaging the spherical element and resilient means for holding said parts in frictional contact.

8. A lamp support comprising a frame, a cap secured to said frame, a socket, a loose frictional element interposed between the cap and socket, and springs connecting the socket to the frame, for holding said parts in frictional contact.

9. A lamp support comprising a frame, a lamp socket within the frame, fingers secured to said socket and adapted to surround a lamp in said socket and springs connecting the frame to said fingers.
10. A lamp holding device comprising a frame, a movable socket within said frame and having frictional contact with the frame so that its movements in the frame are retarded thereby, and springs connecting the socket to the frame and tending to move the socket upwardly in the frame.
11. A lamp holding device having a yieldable framework, a socket yieldably mounted
- within the framework and bearing against one portion thereof, and springs connecting the socket to the framework.
12. A device of the character described having a frame, a lamp support mounted within the frame, frictional retarding means tending to oppose movement of the support within the frame and springs connecting the support to the frame.

In witness whereof, I hereunto subscribe my name this 28th day of December, A. D. 25 1917.

EDWIN D. TILLSON.
